UNITED STATES PATENT OFFICE.

ALBERT S. BLATTERMAN, OF ASBURY PARK, NEW JERSEY, ASSIGNOR, BY MESNE ASSIGNMENTS, TO B. M. C. PATENT COMPANY, OF TRENTON, NEW JERSEY, A CORPORATION OF NEW JERSEY.

COUPLING RADIO FREQUENCY AMPLIFIER.

Application filed June 13, 1922, Serial No. 567,964. Renewed December 3, 1928.

This invention relates to coupling reaction coils or transformers employed in radio frequency amplifiers, particularly in that type comprising three-electrode vacuum tubes.

5 The object of the invention is to provide a novel and efficient construction of coupling reaction coil or transformer, and method of making same, having a minimum self capacity and especially adapted for coupling vacuum tubes.

The construction of such coupling reaction coil or transformer is of great importance in the efficient functioning of an assembled radio frequency amplifier, and in particular, a 15 matter of prime importance is the method of winding the coils on said coupling reactor or transformer. Heretofore it has been considered necessary to wind these coils very carefully with a view to obtaining high efficiency and uniformity in operation in the production of large numbers for commercial use. A prima facie requirement in the construction of coupling reaction coils or transformers in a radio frequency amplifier employing three-electrode vacuum tubes, is that the self-capacity of the said coils shall be kept low and as invariable as possible among a large number of similar units, and expensive machinery and great care which has heretofore been used and exercised in the winding of said coils have been employed to meet these requirements.

I have discovered that the generally accepted idea on this subject is greatly exaggerated and that it is unnecessary to utilize the uniform and carefully constructed windings that have heretofore been employed.

In forming the winding according to this invention, I place the required number of 40 turns in the core slot in a haphazard or random manner. The usual method of winding coils in even layers with successive turns regularly adjacent to one another is purposely avoided, and the greater the departure from 45 regularity in winding, the better, since a purpose of this random winding is to reduce the self-capacity of the coil. Previous conceptions regarding such construction hold that lack of uniformity in the operation of the 50 transformer and excessive self-capacity of the windings will result by the method described, and although such windings have been elsewhere employed in the art, they have been

avoided as undesirable in radio frequency amplifier transformer and coupling coil construction. I have discovered, however, that these views are erroneous, and that if the width of the slots is made relatively narrow, transformers so made are quite uniform and the distributed capacity of the windings so 55 low as to exercise no deleterious effect in their 60 operation.

In the accompanying drawings:

Figure 1 is a diagram of a radio frequency 65 amplifier embodying the invention,

Figure 2 shows the form of core and relation of windings, and

Figure 3 shows a modification for additional windings.

In Fig. 1 is indicated diagrammatically an 70 amplifier of the type comprising my invention. Herein the circuit LC represents the input circuit to the amplifier in which the radio frequency voltage to be amplified originates. Such circuit is connected conventionally on the one hand to the grid electrode G_1 of the vacuum tube 1; and on the other hand to the filament electrode F_1 of the said vacuum tube 1. The plate electrode P_1 of the vacuum tube 1 is connected conventionally to a reaction coil herein shown as a 75 transformer T_1 , comprising a primary winding W_1 , and a secondary winding W_2 . This transformer is designed to be especially effective and efficient for amplification at radio 80 frequencies and comprises a type of coupling 85 means referred to in this invention. The plate electrode P_1 of vacuum tube 1 is connected to one end of the primary W_1 , of the said coupling transformer T_1 , and the other 90 end of the primary W_1 is connected to a battery B_1 , and thence to the filament electrode F_1 of the vacuum tube 1. The secondary winding of the coupling transformer or reaction coil T_1 is connected either to the grid 95 and filament electrodes of a second three-electrode amplifier vacuum tube, as in the case of a multi-stage amplifier, or else to a suitable detector. In Fig. 1 is shown, for the sake of simplicity, the latter connection in which the 100 secondary winding W_2 of the coupling transformer T_1 is connected on the one hand to the grid electrode G_2 of the three-electrode vacuum tube detector 2, and on the other hand to the filament electrode F_2 of the said detector tube. 105

In Fig. 2 is shown an approved construction which I employ in a radio frequency amplifier transformer to be used in combination with three-electrode vacuum tubes for 5 radio frequency amplification. The windings are formed in two narrow slots, S_1 and S_2 , cut in a core of insulating material B. These slots are required to be very narrow. For example—I have built numerous 10 transformers comprising this construction in which the slots are from $\frac{1}{16}$ " to $\frac{1}{8}$ " in width. It is desirable to restrict the width of the slot to a maximum of approximately $\frac{1}{8}$ " and the narrower the slot the better. In Fig. 2 the 15 primary winding W_1 of the transformer is placed in one of the slots and the secondary winding W_2 in the other slot, interchangeably and wound irregularly to reduce self capacity. If the number of turns required 20 for proper functioning of the transformer exceeds the number which it is possible to wind in a single slot, or in two slots, one for the primary and one for the secondary, then I employ a longer core, in which are cut 25 several similar narrow slots and the entire winding is distributed serially in the several slots. This construction is shown on Fig. 3, and is required in preference to winding all of the turns in a single wide slot because by my

construction the self-capacity of the finished 30 winding is restricted to a low value.

While I have described in detail a type of construction comprising adjacent slots whose planes are parallel with one another, other constructions, such for instance as single or 35 multiple slots or grooves or self supporting windings and with primary and secondary windings in the same slot or slots but wound one within the other, will be obvious to those skilled in the art, and do not depart from the 40 spirit of my invention, which specifies only that the windings be very narrow and the several turns thereon disposed heterogeneous- 45 ly or in a haphazard random manner.

I claim:

A coupling transformer for radio frequency amplification comprising a bobbin formed solely of non-magnetic material having relatively narrow slots not to exceed one-eighth of an inch in width and primary and 50 secondary coils wound in said slots the coils being wound in sections, the sections of one coil being arranged in alternate relation with the sections of the other coil.

Signed at New York, in the county of New 55 York and State of New York, this 9th day of June A. D. 1922.

ALBERT S. BLATTERMAN.
